UNITED STATES PATENT OFFICE

VINCENZO MANCINI, OF SCHENECTADY, NEW YORK.

SPRING-WHEEL.

1,078,632.

Specification of Letters Patent. Patented Nov. 18, 1913.

Application filed August 26, 1912. Serial No. 716,971.

To all whom it may concern:

Be it known that I, VINCENZO MANCINI, a subject of the King of Italy, residing at Schenectady, county of Schenectady, and State of New York, have invented certain new and useful Improvements in Spring-Wheels, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a view in side elevation of a spring-wheel embodying one form of my invention, the wheel being partly broken away and shown partly in vertical section for convenience of illustration. Fig. 2 is a similar view of a spring-wheel embodying another form of my invention. Fig. 3 is a central cross-section of the wheel shown in Fig. 1. Fig. 4 is a plan view of a broken-away portion of the rim forming part of the central body of the wheel shown in Fig. 1. Fig. 5 is a plan view of the hub of the wheel shown in Fig. 1. Fig. 6 is a plan view of one of the spoke-socket-plates for connecting the rigid spokes with the rim of the central body of the wheel shown in Fig. 1. Fig. 7 is a similar view of the same showing the rocker-slideway and the seat therefor in position upon said socket-plate. Fig. 8 is a central cross-section of the wheel shown in Fig. 2. Fig. 9 is a broken-away portion of the inner rim of the same. Fig. 10 is a plan view of the hub of the same. Fig. 11 is a plan view of a spoke-socket-plate of the same.

The principal object of the invention is to produce a simple and efficient spring-wheel.

Other objects will appear in connection with the following description.

Referring to Figs. 1 and 3 to 7 inclusive of the drawings, 1 is a rigid outer rim of circular form which may be provided with a solid rubber or other tire, 2.

The central body of the wheel comprises a hub, 3, an inner rim, 4, concentric with the hub, and rigid spokes, 5, connecting together said hub and inner rim. The rigid spokes,

5, are mounted in pairs around the hub as shown in Figs. 1 and 3, each spoke being screwed at its inner end into the hub and at its outer end into a socket-plate, 6, rigidly attached by bolts, 7, to the inner side of the inner rim, 4. Each pair of spokes, 5, forms a pair of guides for a sliding split box, 8, with which is pivotally connected the inner end, 9, of a slide-member, 10, the outer end of which is pivotally connected at 11 with the outer rim, 1.

The inner rim is provided with circumferential slots, 12, through which the respective slide-members, 10, extend, said slots being so formed that the inner rim, 4, affords lateral support to the members, 10, but permits them to have a limited movement in a plane at right angles to the axis of the wheel.

Each of the socket-plates, 6, is provided with a slot, 13, adapted to freely receive, and permit the necessary movement of, the slide-member, 10, and with a longitudinal slideway, 14, adapted to receive a sliding rocker-seat, 15, for a rocker slideway, 16, adapted to receive and closely confine the slide-member, 10, in its sliding movement.

The rocker-seat, 15, is connected by resilient rods, 17, with the hub, 3, said rods being adapted to yieldingly support the respective rocker-seats, 15, with the slide-members, 10, extending in radial lines and the outer rim, 1, concentric with the axis of the wheel.

Each rocker-slideway, 16, is in the form of a middle segment of a circular disk, provided with a slideway aperture, 18, for the member, 10; and the rocker-seat, 15, is of similar circular form so that when the rocker-slideway has been inserted endwise into the seat and then turned to bring its aperture, 18, into position to receive the member, 10, the rocker-slideway will be retained by the seat with freedom to rock thereon.

The rods, 17, are formed in pairs connected together at their inner ends, the inner end of each pair being inserted within an opening, 20, in the hub, 3, and held therein by a screw-bolt, 19.

The inner rim is provided with apertures, 21, alternating with the slots, 12, through which apertures, 21, the rods, 17, can be inserted or removed in pairs.

The resilient rods, 17, constitute spring-members which act through the slide-members, 10, to yieldingly maintain the rim concentric with the axis of the wheel.

5 When the wheel is under load, as shown in Fig. 1, the outer rim, 1, is forced upward relatively to the central body of the wheel causing such of the rods, 17, as are not substantially vertical, to bend more or less, in 10 response to, while yieldingly resisting, the movement of the slide-members, 10.

As the wheel rolls along the roadway under load, the slide-members, 10, are caused to move inward and outward through the 15 respective rocker-slideways, 16, said slideways rocking back and forth and the rocker-seats, 15, sliding back and forth to accommodate themselves to the different positions assumed by the slide-members, 10.

20 Referring to the constructions shown in Figs. 2, 8, 9, 10, and 11, the inner rim, 4, and hub, 3, are connected together by a series of rigid spokes, 22, screwed respectively into the hub and into the sockets, 23, bolted to 25 the inner rim, 4. Each slide-member, 10, is pivotally connected at its inner end to a slide-block, 24, confined within a spoke, 22, in engagement with a coil-spring, 25, which tends to force the block, 24, outward. The 30 slide-member, 10, passes through a rocker-slideway, 26, having trunnions, 27, rotatively mounted in the outer ends of a pair of resilient rods, 28, the inner ends of which rods are rigidly connected to the hub, 3, by 35 means of a screw-bolt, 29, and a pair of lugs, 30, on the hub between which each resilient rod is closely confined. The base of the socket, 23, is formed with slots, 31, adapted to freely receive the respective trunnions, 27, 40 and permit a limited movement of the rocker-slideways, 26, in a plane at right angles to the axis of the wheel. In this construction the coil-springs, 25, assist the resilient rods, 28, in tending to maintain the 45 outer rim, 1, concentric with the axis of the wheel.

What I claim as new and desire to secure by Letters Patent is—

1. A spring-wheel comprising a central body, a rim encircling said central body, slide-members severally having a connection with said rim, and a pivotal connection with said body capable of movement toward and from the center thereof, rocker-slideways for 50 the respective slide-members mounted in connection with said central body with freedom for limited reciprocating movement in a plane at right angles to the axis of the wheel, and spring-members acting through 55 said slide-members to yieldingly maintain the rim concentric with the axis of the wheel.

2. A spring-wheel comprising a central body, a rim encircling said central body, slide-members severally having a connection 60 with said rim, and a pivotal connection with

said body capable of movement toward and from the center thereof, rocker-slideways for the respective slide-members mounted in connection with said central body with freedom for limited reciprocating movement in 70 a plane at right angles to the axis of the wheel, and spring-members opposed to said reciprocating movement of said rocker-slideways.

3. A spring-wheel comprising a central body, a rim encircling said central body, slide-members severally having a connection with said rim, and a pivotal connection with said body capable of movement toward and from the center thereof, rocker-slideways for the respective slide-members mounted in 80 connection with said central body with freedom for limited reciprocating movement in a plane at right angles to the axis of the wheel, and resilient rods rigidly 85 connected at their inner ends to said central body and having their outer ends connected with the respective rocker-slideways.

4. A spring-wheel comprising a central body, a rim encircling said central body, slide-members severally having a connection with said rim and a pivotal connection with said body capable of movement toward and from the center thereof, rocker-slideways for the respective slide-members mounted in 90 connection with said central body with freedom for limited reciprocating movement in a plane at right angles to the axis of the wheel, resilient rods rigidly connected at 95 their inner ends to said central body and having their outer ends connected with the respective rocker-slideways, and coil-springs opposed to inward movement of the respective slide-members.

5. In a spring-wheel and in combination 105 an outer rim, an inner rim; a hub; rigid spoke connections between said hub and inner rim; blocks slidably guided by the respective spokes; resilient rods rigidly connected at their inner ends to said hub; 110 rocker-slideways, each connected with the outer end of a plurality of said resilient rods with freedom for limited reciprocating movement in a plane at right angles to the axis of the wheel; and slide-members movable through the respective rocker-slideways and pivotally connected at their outer ends to the outer rim and at their inner ends to the respective slide-blocks.

6. In a spring-wheel and in combination 120 a hub, an inner rim provided with slots; an outer rim; hollow rigid spokes connecting said hub with said inner rim; slide-blocks within the respective hollow spokes; coil-springs within the respective hollow spokes 125 tending to force the respective slide-blocks outward; resilient rods rigidly connected at their inner ends to said hub; rocker-slideways, each connected with the outer ends of a plurality of said resilient rods with free- 130

dom for limited reciprocating movement in a plane at right angles to the axis of the wheel; and slide-members, movable through the respective rocker-slideways and slots in the inner rim, connected at their outer ends to the outer rim and pivotally connected at their inner ends to the respective slide-blocks,

In testimony whereof, I have hereunto set my hand this 9th day of August, 1912.

VINCENZO MANCINI.
